United States Patent Office

Des. 193,201
Patented July 10, 1962

193,201

BAKING DISH OR SIMILAR ARTICLE

Victor J. Bergeron, Hillsborough, Calif.
(20 Cosmo Place, San Francisco, Calif.)

Filed Nov. 21, 1961, Ser. No. 67,639

Term of patent 14 years

(Cl. D44—15)

FIG. 1

FIG. 2

FIG. 3

I claim:

The ornamental design for a baking dish or similar article, as shown.
